METHOD AND ARRANGEMENT FOR DIMINISHING NOISE IN VACUUM TUBES

Application filed October 28, 1924, Serial No. 746,268, and in Germany December 18, 1923.

- My invention relates to a method and means for diminishing and eliminating the note caused by the use of alternating current for heating the cathode of thermionic tubes, and 5 has for its object to provide such a method and means whereby the note caused by the alternating cathode heating current is compensated by using a rectified current of the same frequency to supply the anode.
- 10 Other objects will be apparent from the following description and claims when taken with the accompanying drawing in which:—
- Fig. 1 is a schematic representation illustrating my invention, and;
- 15 Fig. 2 illustrates a modification.
- Electron tubes whose cathodes are heated by alternating current ordinarily cause a tone of the alternating current frequency and also of double the frequency in the output circuit.
- 20 It is all the same whether the electron tube is used as an amplifier or as an oscillation generator. In the latter case the generated oscillation is modulated by the tones caused by the heating current. Means for diminishing 25 these tones caused by the heating current are known. A very suitable arrangement is, for instance, to arrange an ohmic resistance in parallel to the heating filament and to use the middle of this resistance as the "K"-point, 30 that is, the connection contact of the grid circuit and of the anode circuit. That component of the heating current note which has the same frequency as the heating current can be completely eliminated by this connection.
- 35 On the other hand, a heating current note of the double frequency remains. This note is based upon two causes: Firstly, the heating of the filament and consequently the electron emission slightly pulsates in the rhythm 40 of double the heating current frequency, even when an alternating current of as high as 500 periods per second is employed. Secondly, the potential of the filament in respect to the grid is varied with the double frequency, as 45 the two halves of the filament must be regarded as symmetrical.
- In case the anode voltage is generated by a rectified alternating current, the anode current itself also contains a component of the 50 double frequency of the employed rectified
- alternating current, and this frequency is particularly strong when a two phase alternating current is led through a two-parted rectifier. So the anode current brings in the same disturbing note as the heating current, if the 55 anode alternating current and the heating current have the same frequency. The components caused by the anode current and heating current will strengthen or weaken one another according to the difference of phases 60 of these two currents. This fact is employed by the present invention according to which the phases of the disturbing components caused by the heating voltage and by the anode voltage are compulsively and constant- 65 ly adjusted during the working of the electron tube, so that the two components act against one another and weaken one another.
- Referring to Fig. 1, the transmitting tube *a* acts upon the oscillatory circuit *b* which 70 comprises inductance 1 and capacitance 2. Inductance 1 has a portion connected in the output circuit of tube *a* and also a portion in the input circuit of tube *a* to give the necessary feed back to cause sustained oscillations. 75 The generator *c* acting thru the transformer *d* supplies the heating alternating current. The secondary of transformer *d* is connected to the filament of the tube *a* to which the resistance *e* is connected in parallel, and the middle of this resistance is, as known, the "K"-point. The generator *g* produces a two-phased alternating current of the same frequency as that of the heating current generator *c*. This current is transformed by 80 transformer *h* and rectified by the double rectifier *i*. The alternating current generators *c* and *g* are compulsively connected to one another by the coupling *A*, and it is all the same whether they have a common shaft or 85 not. The coupling *A* contains an arrangement by means of which the rotors of both generators can be adjusted to any desired relative angle. The maximum turning angle corresponds to a phase displacement of 360° 90 between the alternating currents of the two generators. Any phase angle between heating current and anode current can be adjusted by means of this arrangement. According to the invention that phase displace- 95 100

ment is adjusted, for which the disturbing note which, for instance, may be tested by means of an auxiliary detector circuit (not shown) has the least strength.

5 The present invention further provides, that the magnitudes of the disturbing components are so adapted to one another that the disturbing note is eliminated as completely as possible by suitably adjusting the difference of phases. This adaptation can be attained by means of different methods. One possibility is to suitably dimension the magnitude of the capacity q connected in parallel to the rectifier i . When this capacity is equal 10 to zero, the disturbing component caused by the anode current is largest. It becomes less at increasing capacity and disappears at infinite capacity value. That value of the capacity for which the amplitudes of the disturbing components are equal to one another, usually lies between zero and infinity, unless the heating current is exceedingly strong for 15 any reasons.

20 Referring to Fig. 2, there is illustrated another method of adapting the disturbing components to one another. In carrying out this method of reducing hum which has been described in particular and claimed in detail in my copending application #207,417, July 25 21, 1927, the grid-cathode circuit is coupled to the direct current anode circuit, for instance, inductively, in such a way that the alternating current component of the double working frequency which the anode direct current contains, is superimposed on the normal grid direct current or alternating current. Thereby the disturbing component which is brought in by the heating current, is compensated to a certain extent, or, more 30 exactly, it is equalled to the component of the anode note. The right phase for which the disturbing note is a minimum so that it will completely disappear at suitable coupling, may be adjusted, as mentioned above, 35 by regulating the variable coupling of the generators.

40 The arrangement in Fig. 2 is generally the same as Fig. 1, only the direct current anode circuit now contains an inductance m and the grid circuit an inductance coil n . The several parts of Fig. 2 are denoted by the same reference characters as similar parts of Fig. 1. The inductances m and n are coupled to one another by a variable coupling, the sense 45 of which can be reversed. The condenser o bridges over the coupling coil n for the high frequency flowing through the grid circuit of the tube transmitter. The arrangement is adjusted in such a way that first the coils 50 m and n are short-circuited and the phase between the working anode current and the heating current is adjusted to make the disturbing note a minimum by suitably regulating the coupling A ; then the short-circuit is 55 removed from the coils m and n , and then

the disturbing note is further diminished or completely eliminated by suitably adjusting the sense of coupling and the coefficient of coupling.

60 In some cases it may be appropriate to adjust the phases of the disturbing components of the anode current and the grid current only partly by means of the coupling A of the generators g and c by which often only an inaccurate regulation is carried out. For 65 the accurate regulation of the phases, further impedances are inserted in the anode circuit, or grid circuit, by means of which an accurate phase displacement is possible. This can, for instance, be carried out by connecting a capacity p in parallel to the coil m , or a capacity p' in parallel to coil n , and then 70 nearly tuning p and m , or p' and n , to the disturbing frequency. The phase regulation is based upon the knowledge that a coupled 75 circuit near to its resonance possesses a phase varying from 0° to 180° together with the capacity. Of course, it is also possible to 80 displace the phases of the two disturbing components by arranging any other resistances in the anode circuit or direct current 85 grid circuit.

90 Having described my invention, I am entitled to all modifications thereof as fall fairly within the scope of the following claims:—

95 1. The method of diminishing the alternating current hum from thermionic valves the anode cathode circuit and the cathode heating circuit of which are energized from an alternating current source which comprises, 100 supplying the cathode heating circuit with an alternating current of definite frequency, supplying the anode cathode circuit with a current derived from alternating current of the same frequency and adjusting the 105 phase relationship of the two currents to oppose each other.

110 2. The method of diminishing the alternating current hum from thermionic valves, the anode cathode circuit and the cathode heating circuit of which are energized from an alternating current source which comprises, 115 supplying the cathode heating circuit with an alternating current of definite frequency, supplying the anode cathode circuit with a current derived from alternating current of the same frequency and adjusting the phase relationship and magnitude of the two to oppose and compensate each other.

120 3. In radio apparatus, a thermionic valve including a cathode, grid and anode, a source of alternating current for heating the cathode, a grid cathode circuit, an anode cathode circuit, a source of alternating current potential for said anode cathode circuit of the 125 same frequency as said cathode heating current, and means associated therewith for adjusting the phase relationship of the two currents.

130 4. In radio apparatus, a thermionic valve

including a cathode, grid and anode, a source of alternating current for heating the cathode, a grid cathode circuit, an anode cathode circuit, a source of potential for said anode cathode circuit derived by rectifying alternating current of the same frequency as said cathode heating current, means for adjusting the phase relationship of the two currents, and means for relatively adjusting the magnitude of the two currents.

5. In radio apparatus, a thermionic valve including a cathode, grid and anode, a source of alternating current for heating the cathode, a potentiometer connected across said cathode and to said grid, a grid cathode circuit, an anode cathode circuit, a source of potential for said anode cathode circuit of the same frequency as said cathode heating current, and means located substantially at the source of said currents for adjusting the phase relationship thereof.

6. In radio apparatus, a thermionic valve including a cathode, grid and anode, a source of alternating current for heating the cathode, a grid cathode circuit, an anode cathode circuit, a source of alternating current potential for said anode cathode circuit of the same frequency as said cathode heating current, means for adjusting the phase relationship of the two currents, and coupling means for relatively adjusting the magnitude of the two currents.

7. In radio apparatus, a thermionic valve including a cathode, grid and anode, a source of alternating current for heating the cathode, means for connecting said grid to a point having a potential intermediate to that of the terminals of said current source, a grid cathode circuit, an anode cathode circuit, a source of alternating current potential for said anode cathode circuit of the same frequency as said cathode heating current, means for adjusting the phase relationship of the two currents, and capacitive coupling means between said anode cathode circuit and said grid cathode circuit for adjusting the magnitude of the two currents.

8. In radio apparatus, a thermionic valve having cathode, grid and anode electrodes, a source of alternating current for heating the cathode, said grid being connected to a point intermediate of the terminals of said source, a grid cathode circuit, an anode cathode circuit, a source of potential for said anode cathode circuit derived from alternating current of the same frequency as said cathode heating current, and means for adjusting the phase relationship of the two currents.
